US0D1061890S

(12) **United States Design Patent** (10) **Patent No.:** **US D1,061,890 S**
Wei (45) **Date of Patent:** **** Feb. 11, 2025**

(54) **EAR CLEANER**

(71) Applicant: **Wenlan Wei**, Longchang (CN)
(72) Inventor: **Wenlan Wei**, Longchang (CN)

(**) Term: **15 Years**

(21) Appl. No.: **29/970,307**

(22) Filed: **Oct. 28, 2024**

(30) **Foreign Application Priority Data**

Apr. 29, 2024 (CN) 202430251273.8

(51) **LOC (15) Cl.** **24-01**

(52) **U.S. Cl.**

USPC **D24/151**

CLAIM

The ornamental design for an ear cleaner, as shown and described.

DESCRIPTION

FIG. 1 is a front perspective view of an ear cleaner, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines in the drawings illustrate the portions of the ear cleaner, which form no part of the claimed design.

1 Claim, 8 Drawing Sheets
